UNITED STATES PATENT OFFICE

126,262

DESIGN FOR A DRESS OR SIMILAR ARTICLE

Herman Beispel, New York, N. Y.

Application December 21, 1940, Serial No. 97,528

Term of patent 3½ years

To all whom it may concern:

Be it known that I, Herman Beispel, a citizen of the United States, residing in the city, county, and State of New York, have invented a new, original, and ornamental Design for a Dress or Similar Article, of which the following is a specification, reference being had to the accompanying drawing, forming part thereof.

Fig. 1 is a front elevational view of a dress showing my new design.

Fig. 2 is a rear elevational view thereof.

The characteristic feature of my design resides in the combination on the dress disclosed of the specific embroidery on the front thereof, as shown.

I claim:

The ornamental design for a dress or similar article, as shown and described.

HERMAN BEISPEL.
